Thomas Leonard

UNITED STATES PATENT OFFICE.

HENRY E. LEONARD, OF BROOKLYN, NEW YORK, ASSIGNOR TO C. B. COTTRELL & SONS COMPANY, OF NEW YORK, N. Y., A CORPORATION OF DELAWARE.

CUTTING AND FOLDING MACHINE.

1,344,302.

Specification of Letters Patent. Patented June 22, 1920.

Application filed September 25, 1917. Serial No. 193,090.

To all whom it may concern:

Be it known that I, HENRY E. LEONARD, a citizen of the United States, and resident of the borough of Brooklyn, in the city and 5 State of New York, have invented a new and useful Improvement in Cutting and Folding Machines, of which the following is a specification.

In cutting and folding machines there is 10 a tendency of the advance edge of the web from which the sheet has just been cut, to follow around one of the cutters, thus tending to curl the advance edge of the sheet out of its normal path from the cutters to the 15 guides or friction rollers on its way to the grippers of the collecting or folding cylinder.

My invention includes means for imparting longitudinal stiffness to the traveling 20 web to insure its positive and accurate feeding to register. This stiffness is imparted to the web longitudinally of its travel by means, such for instance as guides arranged in staggered order for deflecting portions of 25 the web to opposite sides of a median line, means such as pairs of guides, being provided for guiding the side edges of the web along said median line.

A practical embodiment of my invention 30 is represented in the accompanying drawings in which,

Figure 1 is a detail face view of that part of a cutting and folding machine which includes my invention, the web being shown 35 in connection therewith.

Fig. 2 is a transverse section taken in the plane of the line II—II of Fig. 1.

Fig. 3 is a section taken in the plane of the line III—III of Fig. 1.

40 Fig. 4 is a detail section taken in the plane of the line IV—IV of Fig. 1, and

Fig. 5 is a detail section taken in the plane of the line V—V of Fig. 1.

The web 1 is shown as passed over the 45 web feed roll 2, and from thence downwardly through pairs of guides 3, 4, and through the pair of coacting transverse web cutters 5, 6, to guides or friction rollers and grippers (not shown). The member 3 of 50 each pair of guides is mounted on the bar 7 and the member 4 of each pair of guides is mounted on the bar 8. The lower ends of one of the outside pairs of guides which engage the side edges of the web, are arranged 55 to guide these side edges of the web along a

median line through the cutters. The intermediate pairs of guides are arranged in staggered order for deflecting portions of the web longitudinally of its travel between its side edges to the opposite sides of the 60 median line through the cutters, thus longitudinally stiffening the web to insure its positive and accurate feeding to the guides or friction rollers and grippers by eliminating any curling or transverse waving action 65 of the web.

It is evident that various changes may be resorted to in the construction, form and arrangement of the several parts without departing from the spirit and scope of my 70 invention, and hence I do not wish to limit myself to the particular embodiment shown and described, but

What I claim is:

1. In a machine of the character described, 75 transverse web cutters, means for feeding a web therethrough, and means in advance of the cutters, for oppositely deflecting portions of the web longitudinally of its travel as it passes through the cutters, to stiffen 80 the web for insuring its positive and accurate feeding to register.

2. In a machine of the character described, 85 transverse web cutters, means for feeding a web therethrough, and pairs of coacting guides arranged in staggered order in advance of the cutters, for oppositely deflecting portions of the web longitudinally of its travel as it passes through the cutters, to stiffen 90 the web for insuring its positive and accurate feeding to register.

3. In a machine of the character described, 95 a pair of coacting transverse web cutters, means for feeding a web therethrough and means in advance of the cutters, for deflecting portions of the web longitudinally of its travel as it passes through the cutters, to opposite sides of a median line through the cutters for insuring its positive and accurate feeding to register.

4. In a machine of the character described, 105 a pair of coacting transverse web cutters, means for feeding a web therethrough, and pairs of coacting guides arranged in staggered order in advance of the cutters, for deflecting portions of the web longitudinally of its travel as it passes through the cutters, to opposite sides of a median line through the cutters for insuring its positive and accurate feeding to register.

5. In a machine of the character described, a pair of coacting transverse web cutters, means for feeding a web therethrough, means in advance of the cutters, for deflecting portions of the web longitudinally of its travel between its side edges to opposite sides of a median line through the cutters and means for guiding the side edges of the web along said median line through the 10 cutters.

6. In a machine of the character described, a pair of coacting transverse web cutters, means for feeding a web therethrough, pairs of coacting guides arranged in staggered 15 order in advance of the cutters, for deflecting portions of the web longitudinally of its travel between its side edges to opposite sides of a median line through the cutters, and pairs of coacting guides for guiding the 20 side edges of the web along said median line through the cutters.

7. In a machine of the character described, a web feed roll, a pair of coacting transverse web cutters and means interposed between the web feed roll and cutters for imparting 25 a zigzag form to the web transversely of its travel to longitudinally stiffen the web for insuring its positive and accurate feeding to register.

8. In a machine of the character described, 30 a web feed roll, a pair of coacting transverse web cutters, and pairs of coacting guides arranged in staggered order and interposed between the web feed roll and cutters for imparting a zigzag form to the web transversely of its travel to longitudinally stiffen the web for insuring its positive and accurate feeding to register.

In testimony that I claim the foregoing as my invention, I have signed my name this 40
21st day of September, 1917.

HENRY E. LEONARD
